(57) **CLAIM**

I claim the ornamental design for a computer carrying case, as shown and described.

DESCRIPTION

FIG. 1 is a front perspective view of the computer carrying case;

FIG. 2 is a front view of the computer carrying case;

FIG. 3 is a rear view of the computer carrying case;

FIG. 4 is a left end view of the computer carrying case;

FIG. 5 is a right end view of the computer carrying case;

FIG. 6 is a top view of the computer carrying case; and,

FIG. 7 is a bottom view of the computer carrying case.

The textural treatment shown in FIGS. 1-7, which is understood not to include the portions of the figures showing the zipper teeth, is intended to extend over the entire exterior of the case. The texture shown is not intended to represent any one particular texture. The broken lines describing a pair of handles coupled together, as shown in FIGS. 1-6, are for illustrative purposes only and form no part of the claimed design.
